(57) **CLAIM**

The ornamental design for a raceway assembly, as shown and described.

DESCRIPTION

FIG. 1 is a front top quartering perspective view, showing my new design and illustrating the raceway assembly of the present invention.

FIG. 2 is a right hand side view of the raceway assembly illustrated in FIG. 1 with the left hand side view being a mirror image thereof.

FIG. 3 is a front elevational view of the raceway assembly illustrated in FIGS. 1 and 2, fragmented for convenience of illustration.

FIG. 4 is a rear elevational view of the raceway assembly illustrated in FIGS. 1–3, fragmented for convenience of illustration; and,

FIG. 5 is a top plan view of the raceway assembly illustrated in FIGS. 1–4, fragmented for convenience of illustration, with the bottom view being a mirror image thereof.
